FRANZ LANG, OF MUNICH, GERMANY, ASSIGNOR TO ACRO AKTIENGESELLSCHAFT, OF KUSSNACHT ON THE RIGI, SWITZERLAND

INTERNAL-COMBUSTION ENGINE WITH SELF IGNITION

Application filed May 8, 1925, Serial No. 28,899, and in Germany July 4, 1924.

This invention relates to internal combustion engines with self-ignition in which according to one form of the invention the combustion space consists of two chambers, one of which is provided in the piston and the other remaining even at the top dead center position of the piston stroke within the cylinder, that is to say, a chamber is provided in the cylinder beyond or above the ultimate position reached by the piston-head in the compression stroke.

Motors have been proposed wherein air and fuel are to be separately and successively conducted into a chamber formed in the piston. But since the arrangement thereof is such that they can mix only after reaching said space in the piston, the mixing of the two fluids is unduly retarded and in consequence such mixing is difficult, so that incomplete combustion occurs.

It has, moreover, been proposed to form a projecting chamber or pocket at the top and outside of the piston, said chamber being adapted to enter a pocket extending from the cylinder-head and to receive the fuel from a fuel injecting nozzle in said cylinder-pocket, a vent or vents being arranged at the base of the chamber mounted on the piston. Such an arrangement, however, would not be effective in bringing about a thorough and complete mixture of the fuel with the air in the cylinder head. Incomplete combustion and even failure or difficulty in ignition may result from such an arrangement, as also a gumming up of the fuel injecting valve and injury to the same, since the point of greatest combustion intensity would necessarily be quite close to such part.

An arrangement of parts according to one form of the present invention is distinguished from such devices in various respects, for such arrangement involves the connection of a supplemental chamber within the piston with the remaining space formed in the cylinder by a nozzle-like throttling constriction, the form of the remaining space and the relative arrangement of the fuel and other valves being such that the air-current arising during the compression-stroke will force a stream of air well-mixed with fuel through

said throttling constriction into the chamber within the piston. In this manner an extremely intimate mixture of the fuel with air is secured, which greatly facilitates the ignition of the charge and a complete combustion. 55 To achieve particularly good results in this direction the constricted nozzle-like communicating channel should be made relatively short. I also find it advantageous to arrange said channel in line with or co-axial 60 with the fuel injecting nozzle.

Thus the present invention according to the aforesaid one form thereof comprises in combination the said combustion chamber provided in the piston head, the other combustion chamber remaining even at the top center position of the piston stroke within the cylinder, and a nozzle-like acting arrangement between the said two combustion chambers. This combination serves for the 70 purpose of whirling the air while throttling the same into the first combustion chamber, of facilitating the initiation of the self-ignition and of finally extending at the commencement of the working stroke the ignition to the remaining cylinder space. 75

A particularly effective arrangement embodying the invention according to another form thereof employs the two chambers as before, that is, the chamber provided in the cylinder beyond or above the ultimate position reached by the piston-head in the compression stroke and the supplemental chamber within the piston with the nozzle-like throttling constriction thereto, and also the arrangement of a tapering or funnel-like space or passageway in advance of the nozzle-like constriction and between the same and the fuel injection nozzle or valve and preferably formed as an indentation in the piston head. As hereinafter more fully pointed out, in this other form of the invention the chamber within the piston functions primarily as an air storage chamber, the air being forced into said chamber and stored therein under compression during the compression stroke of the piston and that air being discharged therefrom into the cylinder during the working stroke of the piston to supply air needed for combustion. 85 90 95 100

By this arrangement the valves are moreover preserved from injury and are kept free of combustion residues. Furthermore the degree of compression can be kept lower, 5 while nevertheless an always positively acting self-ignition is insured.

The invention is illustrated diagrammatically and by way of example in the accompanying drawing in which Figure 1 is an axial section through one end of a cylinder and the appertaining piston of an internal combustion engine devised according to one form 10 of the invention, and Figure 2 is a similar illustration showing another form of modification.

Referring to Fig. 1, *a* denotes the piston and *b* the combustion chamber provided therein; *d* denotes the other combustion chamber which remains even at the top center 20 position of the piston stroke within the cylinder; *e* denotes the fuel injection nozzle, *f* the air supply valve, and *g* the discharge valve. Now the chamber *b* is contracted at *c*, this contraction being so shaped that it forms 25 a nozzle of small diameter and length through which the two combustion chambers *b* and *d* communicate with each other. The fuel injecting nozzle or valve *e*, it will be noted, is at a distance from the piston chamber *b*, being separated from the nozzle-like constriction *c* thereof by the width of the chamber 30 *d* in the cylinder. This nozzle *c* may be a separately manufactured part which is inserted into the piston *a*.

The operation of the arrangement of parts so described is such that the air entering the cylinder during the working or suction stroke by air-supply valve *f* is during the following compression-stroke of the piston compressed, whereby a strong air-current through 40 the nozzle-like constriction *c* into the piston-chamber *b* is generated. The fuel issuing from the fuel-injection nozzle *e* toward the end of the compression stroke, undergoes a 45 preliminary mixing with the air in chamber *d* in the cylinder before entering chamber *b* through the constriction *c*. In flowing through the constriction it is then forced into intimate mixture with the air which has been 50 strongly heated at the end of the compression stroke, so that the mixture on entering the chamber, will at once ignite, the combustion thus started being then rapidly communicated to every part of the two chambers.

As shown, it is preferred to arrange the fuel injecting nozzle or valve *e* coaxial or in line 55 with the constriction *c*, so that a portion of the fuel may at once be projected into the interior of the air current entering the chamber *b*, thereby augmenting the mixing action.

In the modification shown in Fig. 2 the constriction and arrangement of the parts is the same as in the device illustrated in Fig. 1, 60 except that the chamber *b* and its constriction

or nozzle *c* are located more deeply in the piston than in Fig. 1, the space *b* in the piston above the nozzle *c* being tapering toward the chamber *b* as funnel-shaped and forming a part of the chamber *d* within the cylinder.

In the form shown in Fig. 2, chamber *b* is not a combustion chamber in the sense that much, if any, of the actual burning or combustion of the fuel takes place within this chamber. Due to the peculiar arrangement 70 of the parts, the air in the compression space, comprising chambers *b* and *d*, is compressed during the compression stroke and most of this air is finally forced and stored, highly compressed, in chamber *b*. When the fuel is injected, ignition takes place in chamber *d* and as the piston continues on the working stroke, air from chamber *b* is discharged to supply the air needed for combustion. In this way combustion continues over a comparatively long part of the working stroke 75 instead of being completed almost immediately after ignition takes place.

I wish it to be understood that instead of only one combustion chamber like *b* with a contraction or nozzle like *c* two or more such chambers and nozzles may be provided in one piston.

As shown in both figures of the drawings, the piston chamber *b* in the illustrative forms 80 of the invention is pear or bulb-shaped.

I find the pear-shaped form of the piston-chamber which enlarges downward from the constriction *c* and is rounded at the bottom 85 particularly advantageous for the proper 100 commingling of the fluids, but of course, my invention generically considered may be embodied in a great variety of forms and is not confined to the one shown.

I claim:

1. An internal combustion-engine with self-ignition comprising a cylinder in combination with a piston, the cylinder being formed with a combustion chamber beyond the dead-center position of the piston-head, 110 a second chamber being formed within the piston below the piston-head and arranged to communicate with the first chamber, and a fuel injecting device arranged in the first chamber.

2. An internal combustion-engine with self-ignition comprising a cylinder in combination with a piston, the cylinder having arranged in its interior a combustion-chamber above or beyond the dead-center position of the piston-head, the piston being formed with another chamber below or behind the piston head and with a constricted nozzle-like communication between the two chambers.

3. An internal combustion-engine with self-ignition comprising a cylinder in combination with a piston working therein, the cylinder having in its interior a combustion chamber above or beyond the dead center position of the piston-head, the piston being 125

- formed with a chamber in its interior and below the piston-head and a nozzle-like communication between the two chambers, a fuel valve being arranged in the first chamber at a distance from the chamber in the piston. 5
4. In the combination set forth in claim 3, the fuel injecting valve being at the top of the combustion chamber in the cylinder. 10
5. In the combination set forth in claim 3, the fuel injecting valve being arranged coaxially with the nozzle-like communication. 15
6. In the combination set forth in claim 3, the piston chamber having a pear or bulb shape, its cross-section increasing from the nozzle-like constriction downward. 20
7. An internal combustion engine with self-ignition, comprising, in combination a chamber provided in the piston and behind the piston head, a combustion chamber remaining even at the top center position of the piston stroke within the cylinder, and a nozzle-like acting entrance to the chamber provided in the piston head. 25
8. An internal combustion engine with self-ignition, comprising, in combination a chamber provided in the piston and behind the piston head, a combustion chamber remaining even at the top center position of the piston stroke within the cylinder, and a nozzle provided to form the communication between the two chambers. 30
9. An internal combustion engine with self-ignition, comprising in combination a chamber provided in the piston head, a combustion chamber remaining even at the top center position of the piston stroke within the cylinder, a nozzle-like acting arrangement between the said two chambers and a funnel-shaped space within the piston, this space forming a part of the second named chamber. 35
10. In an internal combustion engine, a cylinder and piston cooperatively formed to provide a compression space consisting of two chambers, one of decreasing dimensions during the inward stroke of the piston and the other formed within the piston walls, below the piston-head, and of fixed dimensions, the two chambers communicating by a throttling orifice. 45
11. In an internal combustion engine, a cylinder and piston cooperatively formed to provide a compression space consisting of two chambers, one of decreasing dimensions during the inward stroke of the piston and the other formed within the piston walls, below the piston-head, and of fixed dimensions, the two chambers communicating by a throttling orifice, the chamber in the piston storing a combustion-supporting medium during the compression stroke and discharging it during the working stroke. 55
12. An internal combustion-engine with self-ignition comprising a cylinder in combination with a piston, the cylinder being
- formed with a chamber beyond the dead-center position of the piston head, a second chamber being formed within the piston and arranged to communicate with the first chamber, a funnel-shaped space within the piston and communicating with the second chamber, and a fuel-injecting device arranged in the first chamber. 70
13. An internal combustion-engine with self-ignition comprising a cylinder in combination with a piston, the cylinder having arranged in its interior a combustion-chamber above or beyond the dead-center position of the piston-head, the piston being formed with a second chamber below or behind the combustion-chamber in the cylinder and a funnel-shaped space within the piston and with a nozzle-like constriction, the funnel-shaped space communicating with the second chamber through the constriction. 75
14. An internal combustion-engine with self-ignition comprising a cylinder in combination with a piston working therein, the cylinder having in its interior a combustion chamber above or beyond the dead-center position of the piston-head, the piston being formed with a chamber in its interior and a funnel-shaped space opening into the first chamber and in communication with the second chamber in the piston through a constriction, in combination with a fuel-injector in the first chamber and facing the funnel-shaped space. 80
15. An internal combustion-engine with self-ignition, comprising a cylinder in combination with a piston working therein, the cylinder having in its interior a combustion chamber above or beyond the dead-center position of the piston head, the piston being formed with a second chamber below or behind the combustion chamber in the cylinder, a nozzle like acting constriction between said two chambers, a fuel injector and a funnel-shaped space between the mouth of said injector and said constriction, said space opening into the first chamber. 85
16. In an internal combustion engine with self-ignition, a cylinder and piston cooperatively formed to provide a compression space consisting of two chambers, one of decreasing dimensions during the inward stroke of the piston and the other formed within the piston walls, below the piston head, and of fixed dimensions, said piston being formed with a funnel-shaped mixing space opening into said first chamber and communicating with the second chamber by a throttling orifice, the second chamber storing a combustion-supporting medium during the compression stroke and discharging it during the working stroke. 90
